By Wm. O. Bell Atty.

UNITED STATES PATENT OFFICE.

JAMES WILLIAMSON, OF CHICAGO, ILLINOIS.

LIGHTING FIXTURE.

Application filed March 17, 1926. Serial No. 95,173.

This invention relates to a novel and improved lighting fixture and has for its principal object to provide means for supporting a lamp socket so that it may be 5 easily inserted in the cover or removed therefrom without the use of tools.

A further object of the invention is to provide a light socket which is detachably supported wholly by the cover and detachably engaged therewith so that it can be 10 easily removed and replaced.

In the drawings I have shown a selected embodiment of the invention and referring thereto—

15 Fig. 1 is an elevation, partly broken away, and in section, of a fixture embodying the invention;

Fig. 2 is a similar view showing the socket member being applied to or removed from 20 the cover;

Fig. 3 is a sectional elevation;

Fig. 4 is a transverse sectional view on the line 4—4 of Fig. 1; and

25 Fig. 5 is a detail view, partly in section, of the socket member detached from the cover.

Referring to the drawings, 6 is a dome-shaped socket member supported from the arm 7 and provided with an opening 8 to 30 receive the key 9 of the socket member. This socket member comprises a cylindrical body 10 having the threaded shell 11 to receive the base of a lamp and it also has a contact member 12 and usual means 13 for 35 securing the conductor wires thereto. Intermediate of the ends of the body of the socket members are annular flanges 14, 15, spaced apart to accommodate a flat spring 16. The flanges have beveled edges to fit

40 snugly within the cover whereby the socket member is positioned in the cover. The spring is fastened between its ends to the body of the socket member by a screw 17 which clamps the spring tightly against the

45 body and forms the spring, in effect, into two arms projecting on opposite sides of the fastening and secured around the body within the groove 18 between the annular flanges 14, 15. Projections 19 are provided

on the spring arms adjacent the free ends 50 of the spring and these projections extend through openings 20 in the cover.

To assemble the parts the socket member is inserted in the cover and the key through the slot as indicated in Fig. 2 and then the 55 socket member is pushed up in the cover to the position shown in Figs. 1 and 3, whereupon the projections 19 enter the opening 20 and secure the socket member in the cover. The key and the slot register the 60 socket member in proper position in the cover and the flanges 14, 15, also register the socket member in final position in the cover so that the projections will register with the openings and enter them to hold the 65 socket member rigidly in place in the cover. To remove the socket member from the cover it is only necessary to compress the spring on the body of the socket member, by applying pressure to the projections 19, 70 until the projections have been forced sufficiently within the cover to permit the socket member to be pulled out of the cover.

My invention provides a fixture of simple construction, having few parts, which can 75 be readily assembled or separated, and which is strong and substantial. The parts are made of usual materials and in shapes and sizes adapted to different conditions as required.

Changes in the form, construction and arrangement of parts may be made without departing from the invention and I reserve the right to make all such changes as fairly fall within the scope of the following 85 claims.

I claim:

1. A lighting fixture comprising a cover having side openings therein, a socket member comprising a body and having means to 90 receive and support a lamp, annular flanges on the body of said socket member spaced apart to form an annular groove therebetween, a flat spring fastened between its ends to said body within the groove and having 95 its free ends extending outwardly and transverse to the vertical axial line of said body, and projections mounted on each end of

said spring to engage the openings in said cover.

2. A lighting fixture comprising a cover having side openings therein, a socket member comprising a body and having means to receive and support a lamp, annular flanges on the body of said socket member spaced apart to form an annular groove therebetween, a flat spring fastened between its

ends to said body within the groove, said spring being curved and extending outwardly away from said body and transverse to the axial line thereof to form resilient arms, and projections mounted on the outer ends of said spring to engage the openings in said cover.

JAMES WILLIAMSON.
